(57) **CLAIM**

The ornamental design for a hairbrush with multiple compartments as shown and described.

DESCRIPTION

FIG. 1 is a back perspective view of one embodiment of my new design for a hairbrush article, showing separate components.

FIG. 2 is a front view of the embodiment of the hairbrush article design shown in FIG. 1.

FIG. 3 is a one-half rotated back view of the embodiment of the hairbrush article design shown in FIG. 2.

FIG. 4 is a one-quarter rotated side view of the embodiment of the hairbrush article design shown in FIG. 2.

FIG. 5 is a three-quarter rotated side view of the embodiment of the hairbrush article design shown in FIG. 2.

FIG. 6 is a one-half rotated overhead view of the embodiment of the hairbrush article design shown in FIG. 2.

FIG. 7 is a bottom view of the embodiment of the hairbrush article design shown in FIG. 2.

FIG. 8 is also a back perspective view of the embodiment of the hairbrush article design shown in FIG. 1, but showing joined components.

FIG. 9 is a quarter-rotated upright front perspective view of the embodiment of the hairbrush article design shown in FIG. 8.

FIG. 10 is a back perspective view of a second embodiment of my new design for a hairbrush article, showing separate components.

FIG. 11 is a front view of the second embodiment of the hairbrush article design shown in FIG. 10.

FIG. 12 is a one-half rotated back view of the second embodiment of the hairbrush article design shown in FIG. 11.

FIG. 13 is a one-quarter rotated side view of the second embodiment of the hairbrush article design shown in FIG. 11.

FIG. 14 is a three-quarter rotated side view of the second embodiment of the hairbrush article design shown in FIG. 11.

FIG. 15 is a one-half rotated overhead view of the second embodiment of the hairbrush article design shown in FIG. 11.

FIG. 16 is a bottom view of the second embodiment of the hairbrush article design shown in FIG. 11.

FIG. 17 is also a back perspective view of the second embodiment of the hairbrush article design shown in FIG. 10, but showing joined components; and,

FIG. 18 is a quarter-rotated upright front perspective view of the second embodiment of the hairbrush article design shown in FIG. 17.

(Continued)

The broken lines shown represent portions of the article not claimed and form no part of the claimed design.
